COMBINED EYEBROW PENCIL HOLDER AND SHARPENER

Charles Gemora, Los Angeles, Calif.

Application June 11, 1956, Serial No. 41,848

Term of patent 14 years

(Cl. D86—10)

FIG. 1.

FIG. 3.

FIG. 2.

Fig. 1 is a perspective view of the combined eyebrow pencil holder and sharpener therefor embodying my new design, the eyebrow pencil being shown in applied position;

Fig. 2 is a view in side elevation of the same; and

Fig. 3 is a perspective view of the same, the eyebrow pencil being shown in its removed position.

I claim:

The ornamental design for a combined eyebrow pencil holder and sharpener, as shown.

No references cited.
